UNITED STATES PATENT OFFICE.

JOHN MEHL, JR., OF JERSEY CITY, NEW JERSEY.

DESIGN FOR A BELT-BODY.

SPECIFICATION forming part of Design No. 32,602, dated April 24, 1900.

Application filed March 27, 1900. Serial No. 10,405. Term of patent 3½ years.

To all whom it may concern:

Be it known that I, JOHN MEHL, Jr., a citizen of the United States, and a resident of Jersey City, in the county of Hudson and State of New Jersey, have invented and produced a new and original Design for a Belt-Body, of which the following is a specification.

The essential feature of my design consists in a belt-body having its outer surface embellished with ribs, which cross each other at the center of the back and gradually converge as they extend from the center of the back toward the opposite ends of the belt-body.

In the accompanying drawings, Figure 1 is an outside view of the belt-body, and Fig. 2 is a transverse section on the line 2 2 of Fig. 1.

The belt-body as a whole is denoted by A. The ribs, which cross each other at the center of the back and gradually converge toward the opposite ends of the belt-body, are denoted by B B'.

What I claim is—

The design for a belt-body, substantially as herein shown and described.

In testimony that I claim the foregoing as my invention I have signed my name, in presence of two witnesses, this 23d day of March, 1900.

JOHN MEHL, JR.

Witnesses:

FREDK. HAYNES,
EDWARD VIESER.
